US00D958147S

(12) **United States Design Patent** (10) **Patent No.:** **US D958,147 S**
Vautour (45) **Date of Patent:** **** Jul. 19, 2022**

(54) **EARBUD HEADSET CASE**

(71) Applicant: **Skullcandy, Inc.**, Park City, UT (US)

EM 008049399-0002 7/2020

(72) Inventor: **Eran Vautour**, San Francisco, CA (US)

(Continued)

FIG. 1 is a rear perspective view of an earbud headset case according to my new design;

FIG. 2 is front perspective view of the earbud headset case of FIG. 1;

FIG. 3 is a front view of the earbud headset case shown in FIG. 1;

FIG. 4 is a rear view of the earbud headset case shown in FIG. 1;

FIG. 5 is a left side view of the earbud headset case shown in FIG. 1;

FIG. 6 is right side view of the earbud headset case shown in FIG. 1;

FIG. 7 is top view of the earbud headset case shown in FIG. 1; and,

FIG. 8 is a bottom view of the earbud headset case shown in FIG. 1.

The broken lines in FIGS. 1-8 illustrate unclaimed subject matter and do not form any part of the claimed design.

1 Claim, 7 Drawing Sheets
